UNITED STATES PATENT OFFICE.

EDWARD L. BENEDICT, OF SEWICKLEY, PENNSYLVANIA, ASSIGNOR TO PITTSBURGH STEEL COMPANY, OF PITTSBURGH, PENNSYLVANIA, A CORPORATION OF PENNSYLVANIA.

PLASTER GROUND.

Application filed June 21, 1922. Serial No. 569,784.

To all whom it may concern:

Be it known that I, EDWARD L. BENEDICT, a citizen of the United States, and resident of Sewickley, in the county of Allegheny and State of Pennsylvania, have invented a new and useful Improvement in Plaster Grounds; and I do hereby declare the following to be a full, clear, and exact description thereof.

10 My invention relates to a plaster ground or backing for plaster or cement coated walls.

In an application filed by me on the 15th day of July, 1921, Serial No. 484,925, I have 15 set forth and claimed a wire fabric composed of strand-wires and stay-wires connected at their points of intersections, and bends formed in said wires between the points of intersection off-set from the plane 20 of the fabric, with a sheet of building paper perforated to receive the said bends, and a retaining member of wire passing through the loops of said bends, whereby the paper is held securely in place so that when said 25 fabric is secured to the studding the plaster may be applied in the usual manner, the wire fabric acting to bind and hold the plaster in place.

While the bends and the wire retaining 30 member, as above set forth, will be on one side of the paper and will act as a binder for the plaster applied to that side, my present invention when used with the fabric of the above application will give increased 35 holding capacity for the plaster.

The object of my invention is to provide a 40 plaster ground or backing for plaster or cement, coated walls, in which such a fabric as above described can be used for a solid partition where the wire mesh is only employed on one side of the building paper, and to these ends my invention consists in 45 perforating the paper so that when the plaster is applied to the side of the ground or backing at which the wire mesh is located the plaster will pass through the perforations in the paper, and will form buttons or projections which, when the plaster hardens, will form a roughened surface on that 50 side of the backing or paper, so that when the plaster is applied these buttons or projections will act to bind and lock the plaster securely in position to form a solid partition wall.

55 In the accompanying drawing, Fig. 1 is a

plan view of one side of my improved plaster ground or backing; Fig. 2 is a like view of the opposite side; Fig. 3 is an edge view showing the backing connected to the studding; Fig. 4 is a side view; Fig. 5 is a vertical sectional view, showing the plaster applied to one side of the backing; Fig. 6 is a like view showing the plaster applied to both sides of the backing; Fig. 7 is a section on the line 7—7, Fig. 5; and Fig. 8 is a section on the line 8—8, Fig. 6.

I have illustrated my invention in connection with a wire fabric which forms the invention of the above-named application, although it is apparent that it is not limited to this particular form of construction.

The numeral 2 designates the strand-wires and 3 the stay-wires, the strand wires having the bends 4 formed therein between the points of intersection, said bends passing through the openings 5 in the building paper 6. In order to hold the building paper in position the retaining wires 7 pass through the loops of said bends, and the ends of said retaining wires are bent, as at 8, around the marginal strand-wires.

The building paper 6 has the perforations 9 formed at suitable intervals through which the plaster passes when applied to one side of the backing, as will more fully hereinafter appear.

In making a solid partition, the ground or backing is connected to suitable studding which, in the present instance, is illustrated as consisting of the vertical channel-members 10 and any suitable means of securing the backing to said channels may be employed. The plaster is first applied to that side of the ground or backing on which the wire fabric, composed of the strand-wires 2 and stay-wires 3, is located, and the plaster will be secured in place by the wire mesh, and will completely embed the same and at the same time will pass through the perforations 9, as clearly indicated in Fig. 5, forming buttons or hook-like projections. The plaster, being soft when applied, will naturally turn downwardly. As soon as the plaster hardens the plaster may then be applied to the opposite side of the backing, and these buttons or projections will act to bind and lock the plaster, and the plaster is applied of such thickness as to completely embed the studding, as shown in Fig. 8.

In this manner I provide a ground or

backing for plaster or cement coated walls in which it is only necessary to use the wire mesh on one side of the paper, thereby greatly reducing the cost, and by providing 5 the paper with the perforations the plaster applied to one side acts also as a lock or bond for the plaster to be applied to the opposite side.

It is obvious that this ground or backing 10 may be made up in sections in the factory for shipment to the point of use, or may be constructed at the point of use in the manner above set forth.

Where my invention is used for ceiling 15 construction, when the plaster is applied it will pass through the perforations and form mushroom-like protuberances which will lock and hold the plaster securely in place.

What I claim is:

A plaster ground or backing composed of 20 strand wires and stay wires connected at their points of intersection, and rearwardly extending bends formed in said wires between the points of intersection in said frame or plane of the fabric, a substantially 25 flat sheet of continuous surface material through which said bends extend, said sheet having perforations formed therein for the entrance of a portion of the plaster applied to the front of the sheet, and a retaining 30 member engaging the loops of said bends, that portion of the plaster which extends through said perforations serving as a locking means for plaster applied to the rear side of said sheet.

In testimony whereof I, the said EDWARD L. BENEDICT, have hereunto set my hand.

EDWARD L. BENEDICT.
